UNITED STATES PATENT OFFICE

124,112

DESIGN FOR A TEXTILE FABRIC

Jack Rubin, New York, N. Y.

Application November 25, 1940, Serial No. 96,791

Term of patent 3½ years

To all whom it may concern:

Be it known that Jack Rubin, a citizen of the United States and resident of New York city, in the county of New York, State of New York, has invented a new, original, and ornamental Design for a Textile Fabric, of which the following is a specification, reference being had to the accompanying drawing, forming part thereof, and in which,

The single figure of the drawing illustrates a textile fabric, embodying my new design.

I claim:

The ornamental design for a textile fabric, substantially as shown.

JACK RUBIN.
